UNITED STATES PATENT OFFICE

159,759

PORTABLE BARBECUE

Elmer Skelton, Joplin, Mo.

Application April 5, 1948, Serial No. 145,541

Term of patent 14 years

(Cl. D81—10)

To all whom it may concern:

Be it known that I, Elmer Skelton, a citizen of the United States, residing at Joplin, in the county of Jasper and State of Missouri, have invented a new, original, and ornamental Design for a Portable Barbecue, of which the following is a specification, reference being had to the accompanying drawing, forming a part thereof.

Fig. 1 is a side elevational view of the portable barbecue, showing my new design.

Fig. 2 is a front end elevational view of the barbecue oven with side doors in open position and top removed.

Fig. 3 is a top plan view of the portable barbecue; and,

Fig. 4 is a rear elevational view thereof.

I claim:

The ornamental design for a portable barbecue, as shown.

ELMER SKELTON.
